UNITED STATES PATENT OFFICE.

WILLIAM E. WINE, OF TOLEDO, OHIO, ASSIGNOR TO THE TRACTOR GRIP WHEEL COMPANY, OF TOLEDO, OHIO, A CORPORATION OF OHIO.

TRACTION SHOE.

Application filed April 22, 1925. Serial No. 24,942.

The object of this invention is to provide a traction shoe particularly adapted for use on a frozen surface, such as ice and which shall have means to dig into the ice, or the like, to effectually prevent slippage and which shall at the same time be cheaply and efficiently made and shall be rugged in character so as to resist wear of all kinds.

In the accompanying drawing in which I have shown a selected embodiment of my invention:

Fig. 1 is an elevation of a wheel having my improved shoe attached thereto, and showing the shoe in section.

Fig. 2 is an outer plan view of the shoe and

Fig. 3 is a side elevation taken on the line 3—3 of Fig. 2.

Referring now to the drawing, the numeral 1 designates the rim of a wheel of any suitable construction, but shown herein as carrying the teeth 2 to co-operate with the ribs 3 and transverse bar 4 of the shoe to form a driving engagement therewith. In this embodiment the shoe is loosely held on the wheel by the holder 5 loosely engaging the transverse bar 4.

Referring particularly to Figs. 2 and 3, it will be seen that my shoe comprises a plurality of longitudinally extending ribs 6, 7, 8 and 9, these ribs being provided adjacent their ends with projections 10. While I have shown these projections adjacent the ends, it is to be understood that they may be conveniently provided at any part of the rib where it may be found to be desirable.

Connecting the ribs are a plurality of transversely extending webs 11 and 12. The webs 11 extend between the ribs 6 and 7 and 8 and 9 respectively and it is seen that they are in alignment with each other and that the central webs 11 are also in alignment with the transverse bar 4 and form in effect an extension of the bar so that it extends entirely across the shoe. The end webs 11 may, if desired, be extended outwardly at one side of the shoe, as shown at 11' and join the longitudinally extending ribs 13, which are also provided with projections 14. The transverse webs 12 are preferably offset from the webs 11, and by this means a stronger structure is provided in that, instead of having one continuous web 11 of a compara-

tively long span, three webs of short span are provided. Short longitudinal ribs 15 connect the webs 12 with the edges of the shoe, and have projections 10 at their intersections with the webs.

As will be best seen in Fig. 3 the transverse webs are provided with projections 16, the highest points of which coincide with the highest points of the projections 10, or in other words, the webs and ribs are provided with projections at their intersections. By this means an extremely rigid and rugged structure is produced having formed thereon what are generally termed "ice grousers", and it will be noted that these grousers are formed integral with the shoe and in such a manner as to be easily made by a casting operation. By having the grousers formed at the intersections of webs and ribs, these intersecting members effectually brace and reinforce each other and provide a shoe of maximum strength for the purpose desired. By adopting this form I make it possible to extend the shoe a substantial distance beyond the edges of the rim, as shown in Fig. 2 without danger of breaking or buckling.

I am aware that changes in the form, construction and arrangement of parts may be made without departing from the spirit and without sacrificing the advantages of the invention and I reserve the right to make all such changes as fairly fall within the scope of the following claims.

I claim:

1. As an improved article of manufacture, a friction shoe having a plurality of longitudinally extending ribs provided with projections, transverse webs connecting said ribs, said webs being alternately spaced, and a transverse bar to form driving connection with the teeth of a wheel, said bar being in alignment with the central transverse webs.

2. As an improved article of manufacture, a friction shoe having a plurality of longitudinally extending ribs provided with projections, transverse webs connecting said ribs, said webs being alternately spaced, and a transverse bar to form driving connection with the teeth of a wheel, said bar being in alignment with the central transverse webs, the webs upon opposite sides of said bar having short longitudinal ribs extended therefrom toward opposite ends of the shoe.

3. As an improved article of manufacture, a friction shoe having a plurality of longitudinally extending ribs provided with projections, transverse webs connecting said ribs, 5 said webs being alternately spaced, a transverse bar to form driving connection with the teeth of a wheel, said bar being in alinement

with the central transverse webs, the webs upon opposite sides of said bar having short longitudinal ribs extended therefrom toward 10 opposite ends of the shoe, and a holder loosely engaging the said transverse bar.

WILLIAM E. WINE.
